UNITED STATES PATENT OFFICE

171,472

AQUARIUM BREEDING TRAP

Harding W. Willinger and Herbert N. Nestler,
New York, N. Y.

Application February 11, 1953, Serial No. 23,558

Term of patent 14 years

(Cl. D91—2)

To all whom it may concern:

Be it known that we, Harding W. Willinger and Herbert N. Nestler, citizens of the United States, residing in New York, N. Y., have invented a new, original, and ornamental Design for an Aquarium Breeding Trap, of which the following is a specification, reference being had to the accompanying drawing, forming part thereof.

Figure 1 is a top plan view of an aquarium breeding trap, showing our new design;

Figure 2 is a front elevational view thereof; and

Figure 3 is a side elevational view.

The end and side not shown are like the respective end and side shown.

We claim:

The ornamental design for an aquarium breeding trap, substantially as shown and described.

HARDING W. WILLINGER.
HERBERT N. NESTLER.
